UNITED STATES PATENT OFFICE

WILLIAM G. BLACK, OF CLEVELAND, OHIO

DOOR HOLDING DEVICE

Application filed January 25, 1928. Serial No. 249,297.

This invention relates to door holders and more particularly to devices for holding garage doors in a desired open position or a closed position.

5 The main object of the invention is to provide a door holder of simple and inexpensive and practical construction, which is conveniently and easily operated for causing the doors to be held or for releasing the same.

10 Another object of the invention is to utilize the action of the coils of a coiled spring for gripping a rod to lock the rod against movement and thereby hold doors in open or closed positions.

15 With the above and other objects in view, the invention will be hereinafter fully described with reference to the accompanying drawings, and the novel features thereof will be distinctly pointed out in the appended 20 claims.

In the drawings, similar characters of reference are used to designate corresponding parts.

Figure 1 is a horizontal sectional view of a 25 building at the door opening thereof, the cross beam of the door opening being removed, which view illustrates one of the doors in open position and the other in closed position with devices constructed in accordance with 30 my invention applied thereto,

Fig. 2 is a vertical sectional view, on an enlarged scale, taken on line 2—2 of Figure 1,

Fig. 3 is a front elevation of the bracket 35 member with a portion of the rod encircled by the coiled spring in gripping position,

Fig. 4 is a side elevation of Fig. 3,

Fig. 5 is a sectional view taken on line 5—5 40 of Fig. 3,

Fig. 6 is a similar view taken on line 6—6 45 of Fig. 3, and

Fig. 7 is an end view of the lug side of the bracket member.

Referring to the drawings, 1 and 2 represent 45 a pair of doors hinged as at 3 to the wall of the garage adjacent the door opening 4, and 5 indicates the cross-beam of said door opening. Fixed in each door near the upper ends thereof is an eye member 6 for receiving the turned down end 7 of a rod 8,

which is loosely mounted in aligning openings, indicated by 9, of the opposite sides 10 and 11 of a bracket member 12. A cross pin 13 retains the end 7 of the rod 8 in the eye member 6. The bracket member 12 is 55 pivotally connected at 14 to a supporting plate 15, which is fixed to the cross-beam 5 of the door opening by screws or bolts at 16.

For locking the slidably mounted rod 8 to the bracket member 12 so as to hold the door against movement, a coiled spring 17 of suitable strength is arranged upon said rod between the sides 10 and 11 of the bracket member 12 for normally gripping the rod. One end 18 of the coiled spring 17 is bent at a 60 right angle and passes through an opening 19 of the side 10 of the bracket member 12 for holding the same, and the other end of said coiled spring provides a lever arm 20 for operating said coiled spring. The arm 20 terminates in an eye or loop 21 for the attachment of a pull-chain or cord 22 for convenience in operating the coiled spring 17. The side 11 of the bracket member 12 is slotted vertically at 23 and one of the side portions thereof is bent inwardly to provide a lug or shoulder 24, under which the arm 20 of the coiled spring 17 may be retained to hold the coiled spring in released position 70 around the rod 8. The inner corner of the lug 24 is preferably beveled at 25 to better retain the arm 21.

Operation: The coiled spring 17 normally grips the rod 8 and prevents sliding movement thereof. When the arm 20 is pulled downwardly and swung under the lug 24 by means of the chain 22, the coils of the coiled spring 17 open and thereby release the rod 8, and as the bracket member 12 is pivotally supported, the door may be moved to its open or closed position. By pulling upon the chain 22 and disengaging the arm 20 of the coiled spring from the lug 24, the coils of said coiled spring close upon and grip the rod 8 thereby locking 80 said rod and the door against movement.

It will be understood that slight changes in the details of construction may be made within the scope of the claims.

Having fully described my invention, what 100 I claim is:

1. In a door holder, the combination of a rod, a coil spring adapted to normally grip the rod, one end of the coil spring being fixed, and the other end of the coil spring extending at an obtuse angle therefrom for providing a lever arm for manually operating said coil spring and causing it to release said rod.
2. In a door holder, the combination of a rod, a coil spring adapted to normally grip the rod, one end of the coil spring being fixed and the other end of the coil spring extending at an obtuse angle therefrom for providing a lever arm for manually operating said coil spring and causing it to release said rod, and means for retaining said lever arm when in position for causing said coil spring to release said rod.
3. In a door holder, the combination of a rod, a pivotally supported bracket, the rod being slidably mounted in the bracket, a coil spring encircling said rod, the coil spring having one end fixed to said bracket, and the other end of the coil spring extending at an obtuse angle from said first end for serving as a lever arm for manually actuating said coil spring to cause it to grip and release said rod.
4. In a door holder, the combination of a rod, a pivotally supported bracket, the rod being slidably mounted in the bracket, a coil spring encircling said rod, the coil spring having one end fixed to said bracket, the other end of the coil spring extending at an obtuse angle from said first end for serving as a lever arm for manually actuating said coil spring to cause it to grip and release said rod, and the bracket having means adapted to retain said arm in a set position.
5. In a door holder, the combination of a rod, a pivotally supported bracket, the bracket having a pair of sides and aligning openings therethrough, the rod being slidably mounted in said openings, a coil spring encircling said rod between said sides, one end of the coil spring being fixed to one of said sides, the other end of said coil spring extending at an obtuse angle from said first end for serving as an arm for manually actuating said coil spring, and the other side of said bracket being slotted and a portion thereof bent inwardly for providing a lug adapted to retain said arm for holding the coil spring in a set position.

In testimony whereof I affix my signature.
WILLIAM G. BLACK.
